UNITED STATES PATENT OFFICE.

SAMUEL A. RICHARDS, OF NOVA, OHIO.

WAGON-FRAME.

SPECIFICATION forming part of Letters Patent No. 371,854, dated October 18, 1887.

Application filed May 11, 1887. Serial No. 237,885. (No model.)

To all whom it may concern:

Be it known that I, SAMUEL A. RICHARDS, a citizen of the United States, residing at Nova, in the county of Ashland and State of Ohio, 5 have invented a new and useful Improvement in Wagon-Frames, of which the following is a specification.

My invention relates to an improvement in wagon-frames; and it consists in the construction 10 and arrangement of the parts of the same, which will be more fully hereinafter described, and pointed out in the claims.

The object of my invention is to provide a wagon-frame which is especially adapted for use 15 in connection with heavy wagons, and which is simple and effective in its construction, strong and durable, easily handled, and readily understood and operated, positive in its result, readily applied in connection with any 20 form of wagon, and cheaply manufactured. I attain this object by the construction illustrated in the accompanying drawings, wherein like letters of reference indicate corresponding parts in the several views, and in which—

25 Figure 1 is a perspective view of my improved wagon-frame. Fig. 2 is a top plan view of the same. Fig. 3 is a longitudinal vertical section. Fig. 4 is a top plan view of the whiffle-tree removed. Fig. 5 is a sectional view on the line $x-x$ of Fig. 4.

A indicates the axle-beam, on the top portion of which tongue-hounds B are secured and project outwardly in front of the said axle-beam A and to the rear thereof, and are 35 united in their rear portions by a curved beam, B', and in their front portions have a casting, B'', to which they are rigidly secured and diverge from said casting toward the rear beam, B'. On the top portion of these tongue-hounds B a bolster, C, is secured, in the central portion of which a fifth-wheel or steering-plate may be secured, and above the said bolster C the wagon-bolster C' is mounted, and between the two bolsters C and C' the reach D 40 is secured by the king-bolt E, passing therethrough and through the said bolsters C and C' and down through the axle-beam A.

In the forward part of the tongue-hounds B 45 a small cross-beam, b, is secured, having a spring-plate, b', secured to its under side and projecting forward therefrom on a slight downward incline. The casting B'' is hollow and

open on its under side, and is adapted to receive the inner end of the pole or tongue T. This pole or tongue T has suitable metallic 55 bearing-plates t secured thereto, which bear against the inner sides of the casting B'' and prevent wear of the said tongue by the said casting. The forward portion of the said casting B'' is formed with two curved recesses, b'', 60 which are adapted to receive the hinge-rod t', formed integral with the plate t'', which is secured to the top portion of the tongue T. The extreme rear portion of the tongue T is provided with a metallic lug, t'', which is adapted 65 to bear against the spring b', secured to the cross-bar b, as hereinbefore set forth. By means of this spring bearing upon the rear end of the tongue T the pole is cushioned in its action and is held in a straight line with 70 the frame entire, thereby taking a great deal of strain off the necks of the animals, as will be readily understood.

To the rear portion of the casting B'' two ears, b'', are formed, which embrace a curved 75 arm, b'', which is pivotally connected in said ears b''. The outer end of this arm b'' is provided with an aperture, through which a bolt passes, and is held thereby, and which unites the singletree F, and also retains the pole or 80 tongue T. This hinged arm b'' being in the form of a hinged clevis renders it convenient for the application and adjustment of the singletree in connection with the frame, as it may be readily thrown backward out of the way 85 when the singletree is about to be inserted. It also forms a rigid means for retaining the bolt passing therethrough when the several parts are connected and prevents the same from becoming lost or displaced. 90

To the rear portion of two sides of the casting B'' two brace-rods, G G, are secured, and, curving slightly outward, pass over the bolster C, and are connected to the rear portion of the tongue-hounds B B. At the point where these 95 two brace-rods G G terminate a cross-brace, G', is secured by the same bolt which passes through the end of the braces G G. To the under side of each of the tongue-hounds B B another brace-rod, H, is secured to the same 100 bolt which passes through the braces G at this point, the said brace H passing down under the axle-beam, to which it is secured by suitable bolts, and thence upward under the

tongue-hounds E, where it is secured to the bolt connecting the upper brace, G. Short braces H' H' are secured to the sides of the tongue-hounds B B, and extend down under 5 the axle-beam A, where they are secured by suitable bolts. By means of these braces the several parts of the frame are constructed to resist strain brought to bear thereupon, and at the same time provide a light and compact 10 construction. The novelty and utility of my improved wagon-frame being apparent, it is unnecessary to further enlarge upon the same herein.

Having thus described my invention, I 15 claim—

1. The combination of the tongue-hounds B B, the casting B², the cross-beam b, having a spring, b', secured thereto, the tongue T, the bearing-plates t, and the plate t², having the 20 integral catch-bar t', substantially as described.

2. The combination, with the tongue-hounds B B, united at their rear ends, of the curved cross-beam B', the casting B², to which the front ends of said tongue-hounds are secured, 25 the cross-beam b, the spring b', secured thereto, the ears b⁴, the hinged clevis b⁵, the singletree F, the tongue or pole T, having the metallic projection t' in its rear portion engaging with the spring b', and the bearing-plates t², having 30 the rod t' in connection therewith, substantially as described.

3. The combination, with the tongue-hounds

B B, of the open casting B², connected to the front meeting edges of the said hounds, the removable tongue adapted to be mounted in 35 said casting B², the axle-beam A, and the braces G G', H, and H', substantially as described.

4. The combination, with the tongue T, having the catch-bar t', of the casting B² and the 40 hounds B B, substantially as described.

5. The combination, with the tongue T, having the catch-bolt t' and lug t³, and the casting B², of the hounds B B, the cross-strip b, and the flat spring-plate b', substantially as described. 45

6. The combination of the tongue-hounds B B, the casting B², the cross-beam b, the spring b', the ears b⁴, the hinged clevis b⁵, the braces H, H', and G, the tongue T, and the catch-bar 50 t', substantially as described.

7. The combination, with the hounds B B, having the hollow casting B² arranged at their front meeting ends, of the whiffletree F and the tongue T, the hinged arm b⁵ causing a king-bolt in its free end to pass through the whiffletree and tongue, substantially as described. 55

In testimony that I claim the foregoing as my own I have hereto affixed my signature in presence of two witnesses.

SAMUEL A. RICHARDS.
